Philip Swan Lee & Kennedy

UNITED STATES PATENT OFFICE.

WILLIAM B. HEWITT, OF HOLYOKE, MASSACHUSETTS, ASSIGNOR, BY MESNE ASSIGNMENTS, TO WORTHINGTON PUMP AND MACHINERY CORPORATION, OF NEW YORK, N. Y., A CORPORATION OF VIRGINIA.

DEEP-WELL PUMP.

1,219,307.

Specification of Letters Patent. Patented Mar. 13, 1917.

Application filed February 18, 1916. Serial No. 79,019.

To all whom it may concern:

Be it known that I, WILLIAM B. HEWITT, a citizen of the United States, residing at Holyoke, county of Hampden, and State of Massachusetts, have invented certain new and useful Improvements in Deep-Well Pumps, fully described and represented in the following specification and the accompanying drawings, forming a part of the same.

This invention relates to that class of pumps used especially for deep well pumping, in which a plurality of reciprocating buckets or plungers act on the liquid successively, the especial object of the invention being to increase the capacity and port area of the buckets or plungers of such pumps and to secure a higher volumetric efficiency. The invention aims particularly at the production of a satisfactory triple-acting power pump securing the above results.

In the accompanying drawings forming a part of this specification a triple-acting deep-well pump embodying the invention in its preferred form is shown, and this construction will now be described in detail and the features forming the invention then specifically pointed out in the claims.

30 In the drawings—

Figure 1 is a front view of the pump, with the pump head in elevation and the pump well in section, and with parts of the bucket rods broken away to show the construction, 35 and

Fig. 2 is a vertical central section on the line 2—2 of Fig. 1.

Referring to the drawings, the pump shown is in general construction and arrangement that of my prior Letters Patent No. 1,102,583, dated July 7th, 1914, in which A is the pump head frame mounted above the well B, and carrying the crank shaft C, shown as driven by gear D from power shaft E and pinion F. The crank shaft C carries separate cranks for operating the three buckets, these cranks being set at 120° apart, and connected to the respective buckets by crank rods 10 connected to cross-head guides 11, rods 12, 13 and 16 extending from the cross heads, and yokes 14, 17, for the outer bucket rods, the crank-shaft thus being connected to the central and two outer concentric bucket rods 12, 15, 18 which are

connected, respectively, to the bottom, middle and top buckets G, H, I within the drop tube L terminating in the discharge head K having the discharge pipe 19, all generally as fully described in the above Letters Patent. The drop tube L and bucket rods for pumps 60 of considerable depths will be formed in sections and connected together, so as to sink the pump to any depth desired, these pumps being frequently used for great depths, as well understood in the art.

65 Referring now to the detailed construction of the well portion, each of the bucket rods 12, 15, 18, passes through a suitable packing 20, the inner and intermediate rods thus being packed in the yokes 14 and 17 at 70 the upper ends, respectively, of the intermediate and outer rods, and the outer rods thus being packed in the top plate of the delivery head K. The sections of the inner rod 12 are connected by couplings 1 and the sections of the intermediate rod by couplings 2, the couplings of the outer rod 18 not being shown. The pump buckets are provided with the usual packing rings 3, and, in addition thereto, the two upper buckets H, I 80 are provided with internal guides and packing carried within the respective couplings 21, by which the intermediate and outer rods are coupled to their buckets. The coupling piece 21 carries internally a centering bearing ring 4 in which the respective rods have their bearing, and suitable packing rings 5, 6 are mounted above and below the bearing ring, the bearing ring and packing rings being held in place by cap 7. The upper packing ring 5 prevents the passage of water or lubricant downward from the space between the inner and outer rods into the chamber between the buckets, and the lower rings 6 prevent the upward movement of water from 95 the chamber and form wipers by which the entrance of sand or grit between the rod and bearing ring 4 is prevented. The hollow rods above the combined bearing and packing rings are preferably kept filled with 100 lubricant, as the couplings of the inner rods are liable to bear upon the inclosing rods, and, as shown, inlet pipes 22, 23 communicate, respectively, with the spaces inside the intermediate and outer rods, and the water, 105 oil, or other lubricant may be supplied as desired through flexible pipes 24, while the pump is running, either continuously or the

pipes may be filled first and then the valves controlling pipes 22, 23 closed. Air relief valves for the lubricant spaces are provided at 25. The construction above described, 5 with the combined bearing and packing rings and means for lubricating the annular spaces between the rods is described and claimed in my application Serial No. 815,619, filed January 31st, 1914.

10 Referring now to the present invention, it is important that the capacity of the buckets and their port and valve area, should be as large as possible within the transverse dimensions of the drop tube L, 15 this being especially important in such deep-well pumps. In the construction of such pumps, also, the buckets should be of the same capacity and port and valve area, so as to secure the desired action, and are preferably made duplicates, so that repair parts 20 will fit any bucket, this being important on account of the distance of such Artesian or other deep wells from the factory and the importance of immediate repair and replacement of parts, in order to secure the 25 necessary continuous operation of such pumps, especially when used for irrigation and similar purposes. In such pumps as heretofore constructed, the intermediate rod has reduced considerably the capacity and 30 port and valve area of the top bucket, by its comparatively large size in passing through that bucket, thus in practice reducing the capacity and port and valve area 35 of all the buckets.

I avoid this defect in previous pumps, and largely increase the capacity and port and valve area of the buckets, by reducing the size of the intermediate rod where it 40 passes through the top bucket, so that the portion of the bucket and valve occupied by the intermediate rod is correspondingly lessened. This result is secured in the construction shown by making the section 15^a 45 of the intermediate rod, where it passes through the top bucket I, and for such a length as to permit the movement of the top and intermediate buckets, of a small size as compared with the sections of the 50 intermediate rod 15 above this point where they inclose the coupling or couplings 1 of the rod 12 for the bottom bucket, considerable reduction in size thus being permitted so as to considerably increase the capacity 55 of bucket I and the size of its port and valve 26. As all the buckets and valves are commercially made duplicates, as above explained, this increases correspondingly the size and port and valve area of all the 60 buckets. This reduction in size of the intermediate rod not only increases the bucket capacity and port and valve area through the buckets, but it also increases the allowable speed of operation of the pump, be- 65 cause of the freer flow of the liquid through

the larger ports, and the larger port area also reduces materially the velocity of flow through the buckets and the cutting action of sand on the valve faces is thus practically eliminated, which is especially important in pumping a new well. This reduction in size of the intermediate rod also gives extra room for the bearing ring 4 packing rings 5, 6, and cap 7. In the construction shown, 70 in which the rods are connected to the buckets by sections 8 extending through the valves 26 and secured to the valve seat or body of the bucket below the valve, the section 8 for the top bucket is reduced in size below the coupling 21, as compared 75 with the portion of the rod 18 above the coupling where it incloses the couplings 2 of the intermediate rod 15, thus enabling the desired increase in capacity and port and valve area of the top bucket to be secured. The connecting sections 8 of the other buckets will be made the same size as that of the top bucket, as shown in connection with the intermediate bucket, so as to 80 make the buckets, and valves duplicates, and the capacity and port area of all the buckets 85 the same.

It will be apparent that differential pressure upon the intermediate bucket rod will be caused by the reduction in size of the 90 intermediate rod above the top bucket, unless this is compensated for in some way. While not absolutely necessary, such compensation is preferable, and is secured in the construction shown by reducing the upper end of the intermediate rod correspondingly above the discharge chamber K at coupling 2, or at such point as to be above any couplings of the inner rod 12 inside the intermediate rod. 100

It will be understood that the invention is not limited to the exact construction or arrangement of parts shown, but that these may be modified widely within the invention defined by the claims. 105

What is claimed is:

1. A pump having a plurality of independently movable buckets or plungers arranged in line and having concentric bucket or plunger rods, and having the hollow rod of an intermediate bucket or plunger formed of a larger cross-section for inclosing the inner rod and a smaller cross-section throughout the portion traversed by the upper bucket or plunger whereby space for the inner rod is provided and the reduction in capacity and port and valve area of the upper bucket by the intermediate rod diminished. 115

2. A pump having a plurality of independently movable buckets or plungers arranged in line and having concentric bucket or plunger rods, and having the rod of an intermediate bucket or plunger formed of a larger cross-section for inclosing the inner 125 rod and a smaller cross-section throughout the portion traversed by the upper bucket or plunger whereby space for the inner rod is provided and the reduction in capacity and port and valve area of the upper bucket by the intermediate rod diminished. 130

rod and a smaller cross-section throughout the portion traversed by the upper bucket or plunger, and having the rod of the upper bucket or plunger made of a larger cross-section for inclosing the intermediate rod and a smaller cross-section for connection to its bucket, whereby the required size of the intermediate and outer rods for inclosing the rods inside them is provided, and the reduction in capacity and port and valve area of the upper bucket by the rods diminished.

3. A pump having a plurality of independently movable buckets or plungers arranged in line and having concentric bucket or plunger rods, and having the rod of an intermediate bucket or plunger formed of a larger cross-section for inclosing the inner rod and a smaller cross-section throughout the portion traversed by the upper bucket or plunger, whereby space for the inner rod is provided and the reduction in capacity and port and valve area of the upper bucket by the intermediate rod diminished, said intermediate rod also being reduced in cross-section at its upper end to balance the pressures on the intermediate rod.

4. A pump having a plurality of independently movable buckets or plungers arranged in line and having concentric bucket or plunger rods, and having the rod of an intermediate bucket or plunger formed of a larger cross-section for inclosing the inner rod and a smaller cross-section throughout the portion traversed by the upper bucket or plunger, whereby space for the inner rod is provided and the reduction in capacity and port and valve area of the upper bucket by the intermediate rod diminished, a ring mounted internally on the outer rod to form a bearing for the reduced portion of the intermediate rod, and a packing joint to prevent leakage past the bearing ring.

5. A pump having a plurality of independently movable buckets or plungers arranged in line and having concentric bucket or plunger rods, and having the rod of an intermediate bucket or plunger formed of a larger cross-section for inclosing the inner rod and a smaller cross-section throughout the portion traversed by the upper bucket or plunger, whereby space for the inner rod is provided and the reduction in capacity and port valve area of the upper bucket by the intermediate rod diminished, means to supply lubricant to the annular space between the intermediate and outer rod, a ring mounted internally on the outer rod at the bottom of the lubricant space to form a bearing for the reduced portion of the in-

termediate rod, and a packing joint to prevent leakage past the bearing ring.

6. A pump having a plurality of independently movable buckets or plungers arranged in line and having concentric bucket or plunger rods, and having the rod of an intermediate bucket or plunger formed of a larger cross-section throughout the portion traversed by the upper bucket or plunger, whereby space for the inner rod is provided and the reduction in capacity and port and valve area of the upper bucket by the intermediate rod diminished, a ring mounted internally on the outer rod to form a bearing for the reduced portion of the intermediate rod, a packing joint below the ring to prevent the movement of sand into the space between the ring and rod, and a packing joint above the ring.

7. The combination with independently movable buckets or plungers G, H, I arranged in line vertically and having concentric rods 12, 15, 18, of one or more couplings 1 connecting the sections of the inner rod 12 within intermediate rod 15, and one or more couplings 2 connecting the sections of the intermediate rod 15 within outer rod 18, said intermediate rod having reduced section 15^a below couplings 1 throughout the portion traversed by bucket I.

8. The combination with independently movable buckets or plungers G, H, I arranged in line and having concentric rods 12, 15, 18, of one or more couplings 1 connecting the sections of the inner rod 12 within intermediate rod 15, and one or more couplings 2 connecting the sections of the intermediate rod 15 within outer rod 18, said intermediate rod having reduced section 15^a below couplings 1 throughout the portion traversed by bucket I, and said outer rod 18 being reduced in size below couplings 2 and connected to its bucket by such reduced portion.

9. The combination with independently movable buckets or plungers G, H, I arranged in line and having concentric rods 12, 15, 18, of one or more couplings 1 connecting the sections of the inner rod 12 within intermediate rod 15, and one or more couplings 2 connecting the sections of the intermediate rod 15 within outer rod 18, said intermediate rod having reduced section 15^a below couplings 1 throughout the portion traversed by bucket I, and connection piece 115 8 extending centrally through bucket I and of smaller cross-section than rod 18.

In testimony whereof, I have hereunto set my hand.

WILLIAM B. HEWITT.
